UNITED STATES PATENT OFFICE.

ANDREW W. SWANSON, OF BELLINGHAM, WASHINGTON, ASSIGNOR TO SWANSON EXHAUST BOX COMPANY, OF SEATTLE, WASHINGTON, A CORPORATION OF WASHINGTON.

EXHAUST-BOX.

1,267,010.

Specification of Letters-Patent. Patented May 21, 1918.

Application filed September 26, 1917. Serial No. 193,382.

To all whom it may concern:

Be it known that I, ANDREW W. SWANSON, a subject of the King of Sweden, (who has taken out his first papers as a U. S. citizen,) and resident of Bellingham, county of Whatcom, and State of Washington, have invented certain new and useful Improvements in Exhaust-Boxes, of which the following is a specification.

10 My invention relates to devices of the kind which are generally referred to as exhaust boxes and which are employed for the preliminary heating of cans containing food products, which heating occurs prior to the 15 complete sealing of the cans, and after they have received their contents.

The object of my invention is to provide an apparatus of this kind which, while capable of doing satisfactory work, will be much 20 less in size and cost than the exhaust boxes which are most commonly employed and a device which is superior to such exhaust boxes in many other ways.

My invention consists of certain features 25 of construction and combinations of parts which will be hereinafter described and then particularly pointed out in the claims.

In the accompanying drawings I have shown my invention in the form of construction which is now most preferred by me.

Figure 1 is a side elevation of the device, the same being in major part in longitudinal section.

Fig. 2 is a transverse cross section of the 35 device.

My invention comprises as its most essential parts, a steam jacketed tube through which the filled but unsealed cans are passed and means whereby steam under pressure, 40 or at a temperature which is well above that of atmospheric, 212°, may be injected into said tube so as to contact with the said cans.

The particular manner of embodying this invention in a concrete apparatus is capable of being widely varied. The form 45 of construction herein shown is given merely as illustrative of the principle and as representing the type of construction which is now preferred, as being simple and cheap to 50 make and efficient in use, as well as being strong and unlikely to get out of order.

The heating chamber, as illustrated, consists of two pipes, 1 and 2, these pipes being of different sizes and placed one within the

other. These pipes are joined at their ends 55 by heads 12, which close the annular chamber 3 formed between the pipes. The inner tube is freely open at its ends.

Means are provided for passing the cans through the inner tube. Said means, as 60 herein illustrated, consist of an endless conveyer in the form of a belt 4, one run of which passes through the tube in the direction indicated by the arrow. The cans are placed upon this belt outside of the device 65 and are slowly passed through the same. Any type of conveyer which would secure the desired results, might be employed.

The inner tube 2 has a series of small 70 holes 20 in its side through which steam from the jacketing chamber 3 may be discharged into the inner tube and to contact with the cans 5 which are contained therein. As a convenience in locating these holes so that they may be cleaned out, if for any 75 reason they should become stopped, the outer tube 1 is provided with holes 10 which are, however, stopped when the device is in use, by plugs 11. To secure exact registry of the holes in the outer and inner tube, 80 these holes are preferably drilled after the two tubes have been assembled. It is, therefore, possible to remove the plugs 11 and get at the holes 20 in the inner tube and to clear them of any obstructions which may 85 have lodged therein.

Steam is supplied to the jacketing chamber 3 by any suitable means, as by a pipe 30, which may have a valve 31 therein to control the admission of steam. A gage 31 90 may also be provided to indicate the pressure contained in this steam jacket. The blow-off cock 32 is also shown as connected with the upper part of the steam jacket and drip cocks 33 connected with the lower part 95 of the steam jacket, whereby water of condensation may be blown out.

In order to collect and convey the steam away to a point to where it would cause no trouble, I provide a casing 6 at each end of 100 the device, which casings each have an opening 60 in its outer end wall, of such size as to permit free passage of a can without having any more clearance than may be necessary. Steam discharge pipes 61 connect with each casing and may be led off to a suitable discharge point.

The size of the pipes 1 and 2 which form

- the can heating or exhausting chamber, may be made of anything desired, but preferably is no larger than is necessary to nicely accommodate the cans passing therethrough.
- 5 The length of these pipes may also be varied at will. In practice I have found that a length of twelve feet secures good results. This length may, however, be made greater or less, as desired.
- 10 The steam pressure in the steam jacketing space 3 is preferably carried well above atmospheric. Its temperature is, therefore, correspondingly high and the cans are thus subjected to a higher temperature than that secured in the ordinary exhaust box, and consequently, they are heated to a higher degree much quicker than they would be in the ordinary exhaust box.
- I have found by practical use of this device that the lowering of the pressure of the steam upon discharge into the inner tube without reduction of the heat contents, insures dry steam acting upon the cans and prevents objectionable condensation and drip therefrom. The high temperature of the tubes due to the high pressure contained in the jacket, assists in securing the above results and causes a more rapid heating of the cans by radiation. In consequence, of this, my device may be small, occupying but little floor space and yet will heat the cans to a temperature which efficiently produces the desired results. In Fig. 1 I have shown the casing, which is at the right hand end 30 of the device, as provided with an opening 62 which may be employed for inspection if desired.
- What I claim as my invention is:
1. A device of the character described comprising a steam jacketed passageway, means for conducting cans therethrough and means for successively subjecting the individual cans to the action of jets of live steam substantially throughout the length of their 45 passage through said passageway.
  2. A device for exhausting traveling cans comprising a chamber open to the atmosphere, a steam jacket for said chamber, means for maintaining steam under pressure in said jacket, means for conducting cans through said chamber and means for introducing live steam into said chamber during the passage of the cans therethrough.
  3. A device for exhausting traveling cans comprising an elongated open ended chamber having steam jacketed walls, means for conducting cans through said chamber said cans entering at one end and leaving at the other and means for subjecting said cans to
- the action of live steam during their passage through said chamber.
4. A device for exhausting traveling cans comprising an open ended tube, a jacket about said tube, means for supplying steam under pressure to the jacket, and a can conveyer traveler in the tube, said tube having openings in its walls which establish communication between the interior of the tube and the jacket, said openings being of such restricted area that pressure may be maintained in the jacket. 65
5. An exhaust box device for cans comprising two nested tubes connected at their ends to form a steam jacket between them, the inner tube having steam discharging apertures in its walls connecting with said jacketing space and means for passing the cans through said inner tube. 70
6. A can exhausting device comprising a steam jacketed pipe through which the cans may be passed, means for discharging live steam into said pipe to contact with the cans, steam-collecting and removing casings at each end of the pipe, and means for passing the cans through said pipe. 80
7. A can exhausting device comprising a steam jacketed tube having steam discharging holes in its walls and means for passing cans through the tube. 85
8. A can exhausting device comprising a steam jacketed tube having steam discharging holes in its walls, and a can-conveying belt passing through said tube.
9. A can exhausting device comprising a steam jacketed tube having steam discharging holes in its walls, a steam collecting hood and a discharge pipe therefor connected with each end of the pipe, and a can conveyer passing through the pipe. 95
10. A can exhausting device comprising two concentric tubes connected at their ends to form a closed annular chamber, the inner tube having steam discharging holes in its walls and its ends open to receive the cans, means for supplying steam to the said annular chamber and means for passing cans through the inner tube. 100
11. A can exhausting device comprising two concentric tubes connected at their ends to form a closed annular chamber, the inner tube having steam discharging holes in its walls and its ends open to receive the cans, means for supplying steam to the said annular chamber and a conveyer belt having one run passing through the inner pipe. 110
- Signed at Bellingham, Washington, this 14th day of September, 1917. 115
- ANDREW W. SWANSON.
